UNITED STATES PATENT OFFICE

MAX BLOCH, OF FRANKFORT-ON-THE-MAIN, GERMANY

METHOD AND DEVICE FOR REMOVING THE HAIRS FROM THE SKIN OF FELLS

Application filed April 11, 1930, Serial No. 443,539, and in Germany April 16, 1929.

According to prior patents, in the severing of the hairs from the skins of fells by machines the fell is guided against a rapidly revolving knife-cylinder co-operating with a stationary knife to cut the skin of the fell into strips and sever the hairs from the skin. Because during this procedure the hair is disposed on the same side of the fell as the stationary knife, it banks up before this latter and travels downwards under the influence of gravity in form of fleece. On account of the small weight of the hair and due to the entangling of the single hairs, the hairs already severed are partially carried away with the fell, so that the hairs are cut a second time. This produces a loss, because only the long hairs are valuable.

The object of the invention is to provide a method, by which the above stated disadvantages are avoided. This method consists in feeding the fell to the machine with the hair side of the fell disposed toward the revolving knife cylinder and in removing the hair from the place of cutting by the aid of a current of air, so that the hair is removed from the vicinity of the knives. In this way the repeated cutting of the hair is avoided and the generation of hair-dust obviated, which is a great economical advantage.

Preferably the current of air is caused to travel in a direction opposite to the direction of rotation of the knives and obliquely to the plane of the fell. In this way the escape of the air is facilitated and the formation of dangerous eddies of air is avoided.

According to the invention the current of air acts only at the place of cutting and travels along the stationary knife. The travelling current of air has the advantage of a small consumption of air and protects the fleece of the cut hair from a useless flow of air.

According to the invention the hair is sucked immediately after its cutting off from the skin towards a porous conveying band and therefore retains its form as fleece. This is desirable because the different parts of the fleece are not of the same value and must be sorted before their utilization.

For executing the new method one of the known machines used for the hair-cutting

may be employed, if through the slot of the casing of the knife-cylinder serving for the introduction of the fell a current of air is fed which is directed outwards. By that means the hair severed at each cut will be removed from the cutting place, before the next knife becomes operative. A repeated cutting of the hair, therefore, is impossible.

If the removal of the hairs is made by compressed air, it is preferable to feed the air through the shaft of the rotating cylinder of knives and to permit the air to escape through slots which are arranged immediately in advance of the cutting edges of the respective knives, the slots preferably extending in the same direction as the edges of the knives. In order that the compressed air may escape only during actual cutting movement of the respective knives the air is fed through a pipe which is arranged along the axis of the knife-cylinder and which is provided within the cylinder with a slot which may be adjusted so that it permits the entrance of the air into the channels of the knife-cylinder at the proper instant.

Because as above stated the stationary knife is always rectilineal and the knives secured to the cylinder are curved helically, the slots in the cylinder must also be curved helically, while the slot of the air-pipe must be rectilineal. The helical slots of the cylinder are essentially parallel to the edges of the knives and moreover according to the invention said slots are curved in such a manner that the compressed air escapes at acute angles with respect to radial lines passing through the cutting edges of the knives and opposite to the direction of rotation of the knife-cylinder. Thus the hair cut off will be blown away from the skin, so that it comes out of the reach of the knives.

A second series of air-passages which are parallel to the edges of the knives and essentially radial is provided for blowing away the hairs which may be caught by the edges of the knives.

The cylinder of knives is provided with a foil having a smaller diameter than the circumferential surface in which the edges of the knives are arranged. This foil has the

purpose to avoid the generation of air-eddies, which otherwise might be generated by the protruding knives of the cylinder.

A further object of the invention is to provide a device by means of which the elements of the fleece obtained by the new method are maintained connected with one another. This device consists of a conveying band which is arranged close to the edge of the knives.

Preferably the stationary knife as well as the conveying band is arranged below the cylinder of knives. In this case the operative portion of the band is arranged nearly horizontal and parallel to the stationary knife in order both to support and to carry away the hair cut off.

It is advantageous to employ a porous band and to arrange a sucking device below the operative portion of this band. By this means the hair blown away by the air current will be sucked up and held fast by the conveyor band immediately after its severing from the skin, so that it cannot be jumbled up by the compressed air, but retains its form as fleece.

According to the invention, a turning device is provided to turn the fleece to dispose the points of the hairs upwards, in which position the sorting of the hairs can be effected without trouble.

In the drawing a device for executing the method according to the invention is shown.

Fig. 1 is a vertical section through the machine;

Fig. 2 is a front elevation of the same;

Fig. 3 a vertical cross-section through the cylinder of knives; and

Fig. 4 a similar cross-section through the conveyor-rollers on an enlarged scale.

The two side-frames 1 and 2 of the machine are connected at their tops by a bar 3 and at their bottoms by a plate 4 carrying the motor 4a. In the rear portion of these side-frames the bearings 5, 6 are arranged by which the knife-cylinder 7 is carried. This cylinder carries the knives 8 which are curved helically and the length of which corresponds to the width of the fells to be cut. Moreover the cylinder is provided with a foil 9 having the purpose to guide the compressed air escaping from the interior of the cylinder and to avoid eddies of air during rotation of the cylinder. The cylinder is provided with a bore extending throughout the length of the cylinder and said cylinder moreover has formed therein two series of passages. The passage b of the one series are curved and in cooperation with the bevelled edges of the foil g give to the air passing through them a direction which is oblique to a radial line and opposite to the direction of rotation of the cylinder. The passages c of the other series extend in radial directions, so that the air may escape from the cylinder

in a radial direction. The passages b and c are curved in the direction of the axis helically and parallel to the edges of the knives. The supply of air takes place through a pipe 10, which is connected with the air supply pipe 11, the pipe 10 being provided with a rectilineal slot a which is approximately as long as the cylinder of knives.

The cylinder 7 co-operates with the stationary knife 12 which has a rectilineal edge and which is attached to the guide-plate 13 by means of the bar 13 and the screws 14. This guide-plate carries vertical elongations d disposed in dovetailed guides of the side-frames 1 and 2. In the guides of the side-frames side-plates 16 are arranged, against which the ends of the guide-plate 15 abut and by means of the screws 17, 18 the stationary knife is adapted to be adjusted relative to the cylinder of knives.

Below the edge of the stationary knife the stationary conveyor-rollers 19, 20 are arranged which are connected to each other by the spur-wheels 21, 22 and 23 driven from the grooved pulley 24 by means of the wheels 25 and 26. The pulley 24 is connected by means of a round belt with the belt-pulley 27 secured to the shaft 28. The pulley 27 is driven from the knife-cylinder 7 by means of the pulleys 29 and 30.

The lower conveyor-roller 19 co-operates with the grooved roller 31 which is resiliently journaled. It is carried by two levers 32, which may be oscillated around the pivots 33 and which are connected at their lower ends by the plate 34. The grooved roller 31 carries a pinion 35 (Fig. 2) meshing with a corresponding gear wheel of the conveyor roller 19 to cause rotation of the two conveyor rollers 19 and 31 in opposite directions.

With the conveyor roller 20 an endless band 36 co-operates, which band is guided over the guide-rollers 37, 38 and 39. The last roller 39 is journaled in bearings 40 arranged in the side-frames 1 and 2 and is slowly driven from the intermediate shaft by the aid of conical wheels 41 and 42 and the screw gear 43, 44. The band 36 is porous so that the air can pass through it. Within the space surrounded by the band 36 a tube 61 is arranged which is connected with the suction pipe 45. The tube 61 is open at its upper end and extends nearly to the guide-rollers 37, 38. The guide-roller 37 is journaled in two resilient bearings 46 (Fig. 4), against the noses of which the upper ends of the levers 32 bear. If the conveyor roller 31 is lifted from the roller 19 in horizontal direction, it takes the roller 37 with it. In this position of the rollers the material to be cut may be easily introduced between them.

Near the guide-roller 39 the turning device is arranged which serves for turning the fleece. It consists of the wing 47, the upper side of which is covered by the perforated

plate 48 and on each side carries a trunnion, journaled in the frame element 40. The end of one trunnion is connected by the pipe 49 with the suction pipe 45. The wing 47 may be oscillated by the aid of the handle 50 so that the perforated plate 48 comes into contact with the endless band 36. As soon as it has reached this position, the wing will be connected by means of the hand wheel 51 with the suction pipe. The consequence is that the fleece lying on the conveyor band is sucked up by the wing 47. Then the latter will be returned to its horizontal position and the hair lies now with the points upwards on the plate 48 and can therefore be easily sorted.

The propulsion of the knife cylinder 7 is obtained by the pulley 52 from the motor 4a. The free end of the slotted pipe 10 carries an arm 53, in the upper end of which is arranged a set of screws 54, abutting against the fixed stop 55.

The knife-cylinder is surrounded by a protecting hood 57 rotatable around the pivots 56 (Fig. 1). This hood carries in its lower part a drawer 58 which serves for the reception of the wasting strips of skin and is provided with a strip 62 of sheet metal bearing at its upper part against the knife-cylinder while its edge is spaced from the edge of the stationary knife, so that a slot is formed, through which the fell may be fed to the cylinder-knives. The front side of the machine carries a box 59 of sheet metal, which is closed by a cover 60 and serves also for the reception of the wasting strips of skin.

When adjusting the machine care must be taken that the compressed air escapes from the interior of the knife-cylinder at the proper time to blow away the severed hair. For this purpose the slot *a* of the pipe 10 is adjusted by turning the latter in such a manner, that its communication with the passages *b* becomes operative a short time before a knife of the cylinder begins to act. The hair which has been severed by the preceding knife is therefore blown away before the following knife becomes operative. In order that the adjustment of the slotted pipe 10 may be made with the required accuracy, a set screw 54 is arranged at the upper end of the arm 53.

The passages *c* have the purpose to blow away the strips of skin which may be caught by the knives.

The operation of the machine is as follows: The fell to be cut is inserted with the hair-side directed away from the stationary knife between the conveyor rollers and displaced by these latter against the knife-cylinder 7. As soon as the fell reaches the knives of this cylinder it will be cut in small strips and at the same time the hairs will be cut off. By means of the compressed air escaping outwards the severed hair after each cut will be blown on the conveyor band 36 and retained

thereon by the suction device arranged below the guide rollers 37 and 38. This process is repeated at each cut so long as the fell is displaced by the conveyor rollers 19, 20, 31 and the conveyor band 36. The strips cut from the fell gather themselves for the greatest part in the box 59 of sheet metal while the severed hair remains as fleece on the conveyor band 36 and moves with the latter. If the whole fell is cut, the fleece lies upon that part of the conveyor band which is directed obliquely upwards. Now the fleece must be taken from the conveyor band and turned. This is effected by means of the turning device 47 by oscillating this latter around its pivots so far that the perforated plate 48 comes into contact with the fleece. The latter is now sucked up and lifted from the conveyor band by returning the turning device to its original position so that now the points of the hairs are directed upwards. In this position the fleece will be sorted and then conveyed farther.

What I claim is:—

1. Method for severing the hairs from the skin of fells by introducing the fell between the knives of a hair-cutting machine in such a manner that the knives of the cylinder cut off the hairs from the hair-side of the skin and that the hair severed from the skin is blown away by a current of air in a direction opposite to the direction of rotation of the cylinder-knives in order to remove them out of the reach of the knives.

2. Method for severing the hairs from the skin of fells by introducing the fell between the knives of a hair-cutting machine in such a manner that the knives of the cylinder cut off the hairs from the hair-side of the skin and that the hair severed from the skin is blown away in a direction opposite to the direction of rotation of the cylinder-knives by a current of air becoming operative along the stationary knife only at the place where in each moment the cutting takes place.

3. Method for severing the hairs from the skin of fells by introducing the fell between the knives of a hair-cutting machine in such a manner, that the knives of the cylinder cut off the hairs from the hair-side of the skin and that the hair severed from the skin is blown away in a direction opposite to the direction of rotation of the knife-cylinder by the aid of a current of air on a porous conveyor-band in order to maintain the connection of the fleece.

4. Machine for executing the method of severing the hairs from the skin of fells comprising in combination a stationary knife, and a rotating knife-cylinder arranged on the hair-side of the fell in a casing, a slot in said casing at the cutting place, an air-passage arranged tangentially to the knife-cylinder for blowing an air-current from the interior of the casing in a direction opposite

to the direction of rotation of the cylinder in order to remove the severed hairs from the cutting-place.

5. Machine for severing the hairs from the skin of fells, comprising in combination a casing, surrounding a stationary rectilineal knife and a rotating knife-cylinder with helically curved knives, air-passages in said knife-cylinder connected to a source of compressed air, said air-passages being parallel to the edge of the cylinder-knives and curved corresponding to said edges, a rectilineal slot in the air-supply pipe co-operating with said air-passages in such a manner that the 15 air-current can escape only at that place at which a cutting action takes place.

6. Machine for severing the hairs from the skin of fells comprising in combination a casing, surrounding a stationary knife, and 20 a rotating knife-cylinder, a series of air-passages in said cylinder, connected to a source of compressed air, and deflecting the escaping air current into a nearly tangential direction, a second series of radially arranged 25 air-passages in said cylinder, both series of air-passages being curved according to the helical edge of the knives and arranged parallel to said edge, a slot in the supply pipe of the compressed air for allowing only the 30 escape of air at that place where in each moment of the rotation of the knives a cutting action takes place.

7. Machine for severing the hairs from the skin of fells, comprising in combination a stationary knife, a rotating knife-cylinder, two 35 series of air-passages in said cylinder, a foil having a diameter somewhat smaller than the diameter of the knife-edges, a slot in the supply pipe for compressed air for allowing the 40 escape of air only at the cutting place.

8. Machine for severing the hairs from the skin of fells, comprising in combination a stationary knife, a rotating knife-cylinder, air-passages in said cylinder for blowing an 45 air current towards the cutting place in a direction opposite to the direction of rotation of said cylinder, a porous conveyor-band for the severed hairs and a suction device co-operating with said band for retaining the hair- 50 fleece on said band without troubling the connection of the fleece.

9. Machine for severing the hairs from the skin of fells, comprising in combination a stationary knife, a rotating knife-cylinder, a 55 conveyor-band, a suction device below said band, and a turning device movable to and from a position above said band for turning the hairs with their points upwards.

10. Machine for severing the hairs from the skin of fells, comprising in combination a stationary knife, a rotating knife-cylinder, a conveyor-band, a suction device below said band, a tiltable turning device, connected 60 with a source of suction and movable to and 65 from a position in overlying relation to said

band, and a porous plate in said turning device adapted to be brought into contact with the fleece on said band by movement of said turning device to its first mentioned position and by which the fleece may be sucked up 70 from the conveyor-band and then be turned by movement of the turning device to its second mentioned position.

In testimony whereof I have affixed my signature.

MAX BLOCH.
